Primary Examiner — Doris Clark

(**) Term: **14 Years**

CLAIM

(21) Appl. No.: **29/463,931**

The ornamental design for an interchangeable structural module, as shown and described.

(22) Filed: **Apr. 9, 2014**

DESCRIPTION

(51) **LOC (10) Cl.** **25-01**

FIG. 1 is a perspective view showing my new design for an interchangeable structural module from the front, top, and right side;

(52) **U.S. Cl.**

FIG. 2 is a perspective view showing the design from the front, top and left side;

USPC **D25/138**

FIG. 3 is a perspective view showing the design from the rear, top and left side;

(58) **Field of Classification Search**

FIG. 4 is an alternate perspective view of the design showing the design from the top, rear and left side;

USPC D25/138; 52/64, 235, 238.1, 239,
52/243.1, 415, 434

FIG. 5 is a perspective view showing the design from the bottom, rear and left side;

See application file for complete search history.

FIG. 6 is a front elevational view thereof;

(56) **References Cited**

FIG. 7 is a rear elevational view thereof;

U.S. PATENT DOCUMENTS

FIG. 8 is a right-side elevational view thereof;
